UNITED STATES PATENT OFFICE.

ANDREW B. GRAF, OF CINCINNATI, OHIO.

REBOILER FOR ICE-MACHINES.

1,236,927.

Specification of Letters Patent. Patented Aug. 14, 1917.

Application filed January 27, 1917. Serial No. 144,940.

To all whom it may concern:

Be it known that I, ANDREW B. GRAF, a citizen of the United States, residing at Cincinnati, in the county of Hamilton and State 5 of Ohio, have invented certain new and useful Improvements in Reboilers for Ice-Machines, of which the following is a specification, reference being had to the accompanying drawings.

10 This invention relates to an improved reboiler for ice machines, and has for its primary object to provide an apparatus of this character whereby the use of live steam for the purpose of reheating or reboiling the 15 distilled water in the manufacture of artificial ice, is dispensed with, and the expense incident to the operation of apparatus used in ice manufacture, appreciably reduced.

It is also another important object of the 20 invention to provide a reboiler for ice machines wherein exhaust steam from the operating engine and miscellaneous pumps used in the process of manufacture is utilized as the reheating medium for the water, 25 such exhaust steam being so delivered to the reboiler as to remove the air from the water, together with the grease and oil on the surface thereof, before the water is admitted to the filters.

30 In the manufacture of clear, artificial ice from distilled water, it is necessary that the water be reboiled to free the air therefrom. The distilled water is obtained from condensed exhaust steam, and during the summer 35 months when the atmosphere is from twenty to thirty degrees cooler at night than during the day, the condensation of this exhaust steam is much more rapid at night, so that when the water leaves the condenser, 40 it is cooled to approximately 180°. It is necessary that the temperature of the water again be raised to 212° by reboiling the same with live steam in order to completely free the air from the water. This is, of course, 45 a relatively expensive operation, and the present invention is devised with a view to obviating the necessity of employing live steam for this purpose and yet obtain a reboiler which will be highly efficient in operation.

50 By means of the present invention, the desirable end above referred to is obtained without materially increasing the initial cost of construction of the apparatus.

55 With the above and other objects in view, my invention consists in the novel features

of construction, combination and arrangement of parts to be hereinafter more fully described, claimed and illustrated in the accompanying drawings, in which,

60

Figure 1 is a side elevation of a reboiler for ice machines, illustrating the preferred embodiment of the invention;

Fig. 2 is a longitudinal section thereof;

Fig. 3 is a transverse section taken on the 65 line 3—3 of Fig. 2; and

Fig. 4 is an end elevation.

Referring in detail to the drawings, 5 designates a cylindrical tank or boiler which is suitably constructed to safely withstand 70 a pressure of approximately twenty pounds to the square inch. To this boiler and entering through the top thereof, adjacent one of its ends, a steam exhaust supply pipe 6 is connected. In this pipe 6, exteriorly of 75 the boiler 5, a cruciform coupling head 7 is interposed. A pipe 8 from the condenser (not shown), extends into this head and then longitudinally into the pipe 6 toward the boiler, and is provided with a spray nozzle 9. To the lower end of the pipe 6, within the tank 5, a horizontally disposed pipe 10 is connected, said pipe extending longitudinally of the tank 5 and being supported in a suitable hanger indicated at 11. 80 A plurality of spaced ejection pipes 12 extend transversely of the boiler 5 and beneath the pipe 10, and are suitably coupled to the latter pipe. Each of these transverse ejection pipes 12 is provided in its lower 85 portion with a series of outlet openings 13 disposed at an angle of approximately 30° and directing the water and steam jets toward a skimming dam 14 which is fixed to the bottom of the boiler in any suitable 90 manner adjacent one end thereof.

As seen in Fig. 2 of the drawings, the normal water level is substantially coincident with the upper edge of the dam 14 which is approximately one-third of the capacity 100 of the boiler. The water is automatically maintained at this level by means of a float 15 secured upon the stem 17 of a valve 18. This valve is adapted for engagement upon its seat formed on the wall of a casing 19 105 which is attached to the end of a pipe 20 leading to the filter, (not shown). The side walls of this casing are provided with openings so that the water may freely enter within the same. A rod 21 also extends upwardly from the float 15 and is movable through a housing 22 mounted upon the top 110

of the boiler exteriorly thereof. A spring 23, disposed within said housing, surrounds the rod 21, and the tension of this spring may be suitably adjusted by the nuts 24 threaded on said rod. The float 15 may thus be properly positioned in accordance with the desired water level within the boiler, and the opening of the valve 18 with relation to the water level, predetermined.

10 The upper end of the rod 21 is covered by a removable cap 25 threaded upon the wall of the housing 22. A suitable gage glass, indicated at 26, is mounted upon one end of the boiler 5 so that the level of water within 15 the boiler may be at all times ascertained.

A pipe 27 connects the boiler 5 to the condenser to carry off the surplus exhaust steam to be condensed, and the water therefrom delivered through the pipe 8 into the 20 exhaust steam supply pipe 6. An air outlet valve 28 is also mounted in the top wall of the boiler 5 to release the air collecting in the upper portion of the boiler which is not blown out by the steam jets over the dam 25 14 and through the drain pipe 29 which leads to the sewer. If all of the air does not escape in this way, it will find an outlet through the air valves of the condenser.

In operation, the exhaust steam from the 30 engine and pumps is delivered through the pipe 6 into the feed pipe 10, from which it enters the ejection pipes 12. The steam is delivered from the latter pipes through the angular ports or openings 13 under considerable pressure, against the surface of the water contained in the boiler. The steam blowing over the surface of the water removes all oil or grease which runs over the upper edge of the skimming dam 14 into 40 the end of the boiler and out through the drain pipe 29. When the water in the boiler is at the predetermined level, the float valve 18 opens automatically and allows a certain quantity of the water to escape through 45 the pipe 20 to the filters. The steam leaves the tank 5 through the pipe 27, from which it is delivered to the condenser, the condensed water running back through the pipe 8 from the condenser and being sprayed 50 into the pipe 6 to be there highly heated by the exhaust steam and carried with the steam into the pipes 12. Thus, the condensed water, when delivered through the ports 13 to the boiler 5, is at a boiling temperature, and the air is released therefrom to be exhausted through the valve 28 or escape through the pipe 27 to the condenser.

From the foregoing description, taken in connection with the accompanying drawings, the construction, manner of operation and several advantages of my invention will be clearly and fully understood. By avoiding the necessity of maintaining a separate supply of live steam to the reboiler, 65 I have demonstrated in practice that the

cost of maintenance and operation of ice making machines of this character can be materially reduced. At the same time, it will be observed that the construction of the reboiler is not unduly complicated, but on the other hand, is relatively simple and its initial manufacturing cost will, therefore, be comparatively small. The tank or boiler 5 can, of course, be made of any desired capacity, and while I have shown a 70 particular mounting and arrangement of the float valve herein referred to, this feature of the device might be variously modified and valves of other types substituted thereto to control the intermittent flow of water 75 from the reboiler to the filters. The invention is also susceptible of various other modifications in the form, proportion and arrangement of its several parts and I, therefore, reserve the privilege of adopting 80 all such legitimate changes as may be fairly embodied within the spirit and scope of the invention as claimed.

Having thus fully described my invention, what I desire to claim and secure by 90 Letters Patent is:

1. A reboiler for ice making machines including a tank, an outlet pipe connected to the tank, an automatic valve normally closing the outlet to maintain a predetermined 95 water level within the tank, a skimming dam within said tank, and means for delivering exhaust steam in an angular direction upon the surface of the water to direct the grease and oil therefrom over the skimming dam. 100

2. In a reboiler, a tank, a pipe connection to one end of the tank, an automatic valve normally closing said pipe to maintain a predetermined water level in the tank, a skimming dam arranged in the tank adjacent its opposite end, a drain pipe connected to the latter end of the tank, an exhaust steam supply pipe connected to the tank, a water pipe connection between said supply pipe and the condenser, means for delivering the exhaust steam and the condensed water upon the surface of the water in the tank at an angle with respect thereto to cause foreign accumulations on the surface of the water to flow over the skimming dam, and a pipe connected to the tank and leading to the condenser to conduct the exhaust steam to the latter. 110

3. A reboiler for ice making machines including a tank, a pipe connection to one end of the tank, an automatic valve normally closing said pipe and maintaining a predetermined level of water in the tank, an exhaust steam supply pipe connected to the tank, a pipe connected to said steam supply pipe extending from the condenser to deliver condensed water into said pipe, whereby the temperature of the water is raised to the boiling point, and a plurality 120 125 130

of ejection pipes connected to said steam supply pipe within the tank to deliver the boiling water and exhaust steam upon the surface of the water in the tank.

5. 4. In a reboiler for ice making machines, a tank, a pipe connection to one end of said tank, an automatic valve normally closing said pipe and maintaining the water in the tank at a predetermined level, a skimming 10 dam arranged in the tank adjacent its opposite end, an exhaust steam supply pipe extending into the tank, a plurality of spaced delivery pipes connected to the supply pipe and having ejection orifices 15 singularly disposed toward the skimming dam, a pipe extending from a condenser to deliver condensed water into the exhaust steam supply pipe, whereby said water is heated to the boiling point and delivered with the 20 exhaust steam from the ejection pipes upon the surface of the water in the tank, foreign matter on the surface of the water being directed by the steam jets over the skimming dam, and an outlet pipe for the exhaust steam connected to the tank and leading 25 to the condenser.

5. A reboiler for ice making machines including a tank having an outlet at one end, a skimming dam within the tank limiting 30 the water level therein, and means for delivering steam upon the surface of the water to raise the temperature of the water to the boiling point and direct grease and oil from the water surface over the skimming dam.

6. A reboiler for ice making machines including a tank having an outlet at one end, a skimming dam within the tank limiting 35 the water level therein, a steam pipe connected to the tank, steam delivering means within the tank to deliver the steam in an angular direction upon the surface of the water and direct the grease and oil therefrom over the skimming dam, and means

for discharging condensed steam into the 45 steam supply pipe whereby the same is highly heated prior to its delivery into the tank.

7. A reboiler for ice making machines including a tank having an outlet at one end, 50 a skimming dam within the tank limiting the water level therein, a steam pipe connected to the tank, steam delivering means within the tank to deliver the steam in an angular direction upon the surface of the 55 water and direct the grease and oil therefrom over the skimming dam, and means for spraying condensed steam into the steam supply pipe, whereby the condensed steam is highly heated prior to its delivery into 60 the tank.

8. A reboiler for ice making machines including a tank, means for maintaining a predetermined water level in the tank, and means for delivering a plurality of steam 65 jets in an angular direction upon the surface of the water to raise the temperature of the water to the boiling point and discharge air, grease and oil from the water surface. 70

9. A reboiler for ice making machines including a tank, means for maintaining a predetermined water level within the tank, a steam supply pipe, and a plurality of spaced, transversely disposed, steam delivery pipes within the tank each having a plurality of jet orifices to deliver the steam in an annular direction upon the surface of the water to raise the temperature of the water to the boiling point and discharge the 80 liberated air, grease and oil from the water surface. 75
